CLAIM

The ornamental design for a wrist watch, as shown and described.

DESCRIPTION

FIG. 1 is a perspective view of a wrist watch;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines showing on the drawing disclosure are for illustrative purposes only and form no part of the claimed design.

The patterns shown in broken lines in FIGS. 2, 3, 6 and 7 appear under the ring-shaped transparent cover. So do the patterns in FIG. 1 that correspond to them.
